CLAIM

The ornamental design for a hydrant-shaped container for storing, dispensing, and serving liquids, as shown and described.

DESCRIPTION

FIG. 1 is an exploded top left perspective view of a hydrant-shaped container for storing, dispensing, and serving liquids showing my new design;

FIG. 2 is a top plan view thereof;

FIG. 3 is a bottom plan view thereof;

FIG. 4 is an exploded front elevational view thereof;

FIG. 5 is an exploded rear elevational view thereof;

FIG. 6 is an exploded right side elevational view thereof;

FIG. 7 is an exploded left side elevational view thereof;

FIG. 8 is an exploded sectional view thereof taken along line 8-8 of FIG. 7; and,

FIG. 9 is a front elevational view thereof.

The broken line showing the threads in FIGS. 1-9 are included for the purpose of showing environmental structure and form no part of the claimed design.

1 Claim, 9 Drawing Sheets
